UNITED STATES PATENT OFFICE

JAMES R. HUGHES, OF SOUTH BEND, INDIANA, ASSIGNOR TO THE PIERCE-ARROW
MOTOR CAR COMPANY, OF BUFFALO, NEW YORK, A CORPORATION OF NEW YORK

DESIGN FOR A COMBINED RADIATOR AND FENDER FOR VEHICLES

Application filed July 23, 1932. Serial No. 44,429. Term of patent 14 years.

To all whom it may concern:

Be it known that I, JAMES R. HUGHES, a citizen of the United States of America, a resident of South Bend, in the county of St. Joseph and State of Indiana, have invented a new, original, and ornamental Design for a Combined Radiator and Fender for Vehicles, of which the following is a specification, reference being made to the accompanying drawing, forming a part thereof.

In the drawing, Fig. 1 is a front elevational view and Fig. 2 is a perspective view showing my new design.

I claim:

The ornamental design for a combined radiator and fender for vehicles substantially as shown.

Signed by me at South Bend, Indiana, this 15 day of July, 1932.

JAMES R. HUGHES.
